TOY TRAINING DOLL

Dane B. Coe, Manhattan Beach, Calif., assignor to Innova
Incorporated, Playa Del Ray, Calif.

Original design application Dec. 28, 1970, Ser. No. 26,675.
Divided and this application Jan. 29, 1973, Ser. No.
327,708

Term of patent 14 years

Int. Cl. D21—01
U.S. Cl. D34—4 R

F/5-1

FIG. 2

FIG. 3

FIG. 4

FIG. 1 is a front elevational view of a toy training doll showing my new design;

FIG. 2 is a rear elevational view thereof;

FIG. 3 is a front elevational view with the outer vest unbuttoned and open and the inner vest unsnapped and partially opened; and

FIG. 4 is a side elevational view of the toy training doll.

This is a division of design application Ser. No. 26,675, filed Dec. 28, 1970.

I claim:

The ornamental design for a toy training doll, substantially as shown and described.
